UNITED STATES PATENT OFFICE.

JASPER R. WALKER, OF JACKSONVILLE, FLORIDA.

TURPENTINE-CONDENSER.

1,057,788.

Specification of Letters Patent.

Patented Apr. 1, 1913.

Application filed September 9, 1912. Serial No. 719,468.

To all whom it may concern:

Be it known that I, JASPER R. WALKER, a citizen of the United States, residing at Jacksonville, in the county of Duval and State of Florida, have invented certain new and useful Improvements in Turpentine-Condensers; of which the following is a specification.

My improvement relates to condensers, and more particularly to a form of condenser for turpentine stills.

The object is to provide a simple, cheap and effective condensing means that may be connected to any form of vapor generator. The device is, however, designed principally to meet the requirements of the turpentine industry of which I have made an exhaustive study.

The principal advantages of my improvement are its simplicity of construction and the very quick and economical manner of condensation. Turpentine vapors arising from the heated crude products condense very rapidly when they are once chilled, therefore an ample and properly constructed condenser must be provided and one wherein water chilled surfaces (occupying very little space) must penetrate well into and be distributed well within the condenser compartment.

My device consists, broadly speaking, of three tanks (preferably cylindrical and of copper) the first tank, a primary chilling tank, being provided with a water surrounded worm terminating in a pipe connecting the same with the main condensing and cooling tank, the construction of which will be described in detail later, the last of the three tanks being the well for the finished turpentine product, and the two last mentioned tanks having water cooled jackets.

Referring to the drawings Figure 1 is a sectional elevation of the device, Fig. 2 being a detail of construction of a part of the main condensing tank.

Referring to the several features by numerals, 1 represents a pipe adapted to be connected to any vapor generating means by the coupling 1^a, 2 being the primary water cooling tank having a worm 3 and suitable worm supports 4, while a pipe 5, the continuation of the worm, connects the primary cooling means with the main condensing tank 6. The tank proper has an upper and a lower section joined at 7, a water jacket 8

being formed by the outer wall 9 and the inner wall 10 also joined at 7^a—7^a. The inner compartment 11 of the main condenser wherein the worm discharge pipe 5 empties is provided in its upper section with a plurality of dome shaped leaves 12 having central openings 13 and downwardly sloping outer walls 14 and drain holes 15, the latter being located as shown near the water cooled outer wall 10 of the inner compartment. The lower portion of the inner compartment 11 is a cooling tank for the purpose of receiving the drip of the finished product and cooling the same before it flows into the final well tank. With the object in mind of cooling the finished product I have provided a central water cooled column 16 located in the lower portion of the condensing tank as shown. The worm pipe 5 above referred to enters just above the column 16 and any spirits that may have formed from the chill received in the primary cooling tank will be allowed to drip upon the upper basin portion 17 of the above referred to cooling column and finally find its way down into the main cooling tank through the worm 18 which is as shown carried around the water cooled column 16. An outlet pipe 19 leads from the spirits cooling compartment to the spirits well 20 the well having a water cooled wall 21 and a suitable cover 22. Suitable water supply pipes 23, drain pipes 24 and overflow pipes 25 are fitted as shown together with suitable stop valves for controlling the same. The spirits well is provided with glass gage 26 for determining the depth of liquid and an opening 27 fitted as shown on the pipe 5 for ascertaining the flow therethrough.

28 is an access and observation means through the outer and inner walls 9 and 10 of the condensing tank 6.

The operation of the device is as follows: The vapor passes through the worm in the primary cooling tank 2, thence through the pipe 5 to the water jacketed condensing tank 6 where the final condensation of the vapor is effected, the dome shaped condensing leaves 12 before referred to serving to materially hasten the operation. The drippings from the said leaves are received in the lower portion of the tank 6, whence the product passes to the water cooled spirits well 20 through the outlet pipe 19. The provision of the water cooled column 16, the basin 17

at its top and the worm 18 surrounding a portion thereof has been already referred to and explained.

I will reserve the right in the manufacture of this improvement to make various changes in form and mechanical detail so long as I do not depart from the spirit of the invention as set forth in the claims.

I claim:

- 10 1. A turpentine condenser having a primary water cooled coil, a water cooled condensing means connected therewith, the said condensing means comprising a superimposed main condenser compartment, vapor 15 arresting means disposed around the said compartment, an internally and externally water cooled spirits compartment disposed below the said condenser compartment, and an externally water cooled spirits well 20 joining and connected with the spirits cooling compartment.
2. A condenser having a primary water cooled coil, water cooled condensing means connected therewith, the said condensing 25 means comprising a superimposed main condenser compartment, a plurality of baffle plates disposed therein, a water cooled jacket surrounding the said baffle plates, a cooling

tank disposed below the main condensing compartment, a water cooled jacket disposed 30 around the said cooling tank and a water cooled column disposed within the said tank and a water cooled storage well connected with the said cooling tank.

3. A condenser having a primary water 35 cooled coil, a water cooled condensing means connected therewith, the said condensing means comprising a superimposed main condenser compartment, a plurality of horizontal dome shaped baffle plates disposed therein, a water cooled jacket surrounding the said baffle plates, a cooling tank disposed below the said main condenser compartment, a water cooled jacket disposed around the said cooling tank and a vertically and centrally disposed water column within the said tank and an externally water cooled storage 40 well connected with and adjacent to the said cooling tank.

In testimony whereof I affix my signature 45 in presence of two witnesses.

JASPER R. WALKER.
